FORMING DIE FOR SHAPING TUBES

Haywood G. Dewey, Rochester, N. Y., assignor to
Eastman Kodak Company, Rochester, N. Y., a
corporation of New Jersey

Application June 5, 1937, Serial No. 146,638

3 Claims. (Cl. 153—49)

The present invention relates to forming dies for making tubes from sheet metal blanks and more particularly to the provision of inclined or cammed surfaces upon one of the dies.

It is well recognized that in the deformation of sheet metal blanks by forming dies that the edges of the blank may be turned during the forming operation to abut the outer edges of one of the forming dies and thus seriously hamper subsequent forming steps. This difficulty is particularly evident during the formation by dies of blanks of thin sheet metal.

The primary object of the present invention is the provision on a forming die provided with a forming recess of an inclined surface or surfaces adjoining and sloping toward the forming recess, so as to engage the edges of a partially formed blank and to cam those edges into the forming recess of the die.

Another object of the invention is the provision in a forming die of an auxiliary forming member which sets into one of the dies and which is operated prior to the closure of the dies to preform the sheet metal blank.

A still further object of the invention is the provision of the aforementioned inclined surfaces in spaced relation along the edges of the forming recess in one of the dies and adapted to interengage with complementary recesses in the other die when the dies are completely closed.

Other and further objects of the invention will be apparent or suggested to those skilled in the art by the disclosure which follows.

To these and other ends, the invention consists of certain parts and combinations of parts as hereinafter described, the novel features being pointed out in the appended claims.

Reference is hereby made to the accompanying drawings wherein like reference characters designate similar elements and wherein:

Fig. 1 is a vertical cross-section through a multiple forming tool embodying the forming dies of the invention.

Fig. 2 is an end view of such a multiple forming tool.

Fig. 3 is a vertical transverse cross-section taken on the line 3—3 of Fig. 1.

Fig. 4 is a detail of a yoke and support for the auxiliary forming member.

Fig. 5 is a transverse cross-section through the forming dies just prior to movement of the dies to closed position.

Fig. 6 is a perspective view of the forming dies and showing guide members at each end of one of the dies functioning to hold the blank in posi-

tion during the action of the auxiliary forming member.

Fig. 7 is a cross-section through the auxiliary forming member or rod and taken on the line 7—7 of Fig. 1.

Fig. 8 is also a transverse cross-section of the forming rod but taken on the line 8—8 of Fig. 1.

Fig. 9 is a cross-section on the line 9—9 of Fig. 1 but with the dies in partially closed positions.

The present invention is to be described with respect to a multiple forming tool but it is to be understood that the forming dies of the invention may be applied with equal effectiveness to other types of forming dies irrespective of their use either individually, in multiple, or in combination forming tools or dies.

According to standard practice, the forming tool is placed between bolster members of a press. As illustrated herein, the tool is mounted upon a base member 10 of the press. A lower bolster plate 11 is mounted upon the base member 10 and is provided with a plurality of dowels 12. The upper bolster plate 13 has a plurality of guiding sleeves 14 which fit over the dowels 12 and guide the upper bolster plate 13 in its movement with respect to the lower bolster plate 11. The reciprocating movement of the upper bolster plate 13 is accomplished in the conventional manner by a reciprocating member or ram, not shown, of the press.

The illustrated embodiment of the invention includes a pair of punching dies for cutting the blanks to be formed from strip stock moved transversely of the press. Such a punch press comprises a punch 15 on the lower bolster plate 11 and a stripper plate 17 which is mounted on rods 16 and normally held by springs 16' in the position shown in Fig. 1. Stripper plate 17 is provided with a pair of blank guiding channels 18. A pair of stripper pins 19 are mounted within said punch 15 and are urged upwardly by springs 20.

A blanking die 122 is attached to a die holder 23 on upper bolster plate 13. A stripper pad 22 is mounted for vertical movement within the opening of said blanking die 122. Pressure pins 24 extend through stripper pad 22 and have shoulders bearing thereon. Pressure springs 25 bear on pins 24 normally to maintain said pins 24 and stripper pad 22 in the positions shown in Fig. 1.

Upon operation of the press and movement of bolster plates 11 and 13 toward each other, the blanking die 122 depresses the stripper plate 17 against the action of springs 16'. The stock is preferably in the form of a transversely extend-

ing strip and a blank 21 is formed when the punch 15 enters the blanking die 122. During the return stroke of the press, springs 16' return the stripper plate 17 and strip the stock from punch 15, springs 25 move stripper pad 22 to strip blank 21 from blanking die 122, and stripper pins 19 raise blank 21 from the punch 15 while pressure pins 24 bear on the blank 21 opposite stripper pins 19 and prevent the blank 21 from jumping upwardly or sticking to stripper pad 22. At the conclusion of the punching operation the blank 21 is supported by stripper pins 19 opposite said guiding channels 18 in stripper plate 17.

The forming dies of the invention will next be described. The lower forming die 26 is mounted upon a die holder 27 on lower bolster plate 11. Said lower forming die 26 is provided with a forming recess 28 and with a plurality of bevelled recesses 29, see Fig. 6, which are spaced at intervals along the edges of forming recess 28. Auxiliary forming blocks 30 and 31, see Fig. 9, are positioned at each side of the lower forming die 26, have their upper surfaces level with the blank guiding channels 18 of the punch press, and have projections 30' and 31', respectively. An overhanging guide member 32 is fastened to block 30 and a second overhanging guide member 33 is pivotally mounted on die holder 27. A spring 34 between die holder 27 and overhanging guide member 33 holds said guide member 33 in the position shown in Fig. 3.

A pair of guide members or guide plates 35 are positioned at each end of the lower forming die 26 and are each provided with an opening 36.

35 An auxiliary forming member is actuated by an operating means which moves said auxiliary forming member between the auxiliary forming blocks and into the forming recess of the lower forming die to accomplish a preforming of the blank. Such an auxiliary-forming member may comprise a forming rod 37 which is inserted into a guide block 38. Said guide block 38 includes a vertical post 39 on which a nut 40 and washer 41 are fastened.

45 An intermediate bolster plate 42 is provided with an opening 43 and is guided with respect to die holder 27 by a plurality of dowels 44 thereon and guide sleeves 45 on said intermediate bolster plate 42. A bushing 48 is fastened to intermediate bolster plate 42 by bolts 47 and contains a sleeve 46 within which the vertical post 39 of guide block 38 may move. A pair of springs 49 are provided between guide block 38 and intermediate bolster plate 42 to hold them in the relatively separated position shown in Fig. 4. A plurality of presser feet 50, see Fig. 2, are slidably mounted in upper bolster plate 13 and are urged downwardly by springs 51 encircling each presser foot 50 and fitting into bushings 52 in upper bolster plate 13.

A guide channel 53 for the blanks 21 is provided in block 38 by fastening a guide strip 54 to the lower face thereof. A saddle piece 55 is provided with a recess 56 for fitting over forming rod 37 and said saddle piece 55 is fastened to intermediate bolster plate 42 by a nut 57.

A pair of kicker pins 58 and 59 are slidably mounted in die holder 27 and are normally urged to an upper position, shown in Fig. 1, by springs 60.

75 As the upper bolster plate 13 is moved downwardly by the press, the presser feet 50 strike against the intermediate bolster plate 42 and move it downwardly with respect to the forming rod 37 until the recess 56 partially encircles rod 57

and until said intermediate bolster plate 42 abuts the shoulder of guide block 38. Continued downward movement of bolster plate 13 is transmitted through the springs 51 encircling presser feet 50 to move the forming rod 37 downwardly between the opposite faces of projections 30' and 31', which are spaced a distance equal to the diameter of rod 37 and two thicknesses of blank 21, into the forming recess 28 of the lower forming die 26 to preform the blank 21. It will be noted that openings 36 in the guide plates 35 are just wide enough to receive the forming rod 37 and so that the ends of blank 21 abut against the guide plates 35 during this preliminary forming operation. Such abutment between the ends of blank 21 and guide plates 35 prevents any appreciable movement, such as twisting or spiralling during the forming action of rod 37.

This preliminary forming operation by an auxiliary forming member causes the edges of blank 21 to be turned upwardly and present its edges to the upper forming die. Under this condition, any flat surface adjacent the forming recess of an ordinary upper forming die would abut against these edges of blank 21 and either cause excessive wear upon the forming die or mutilation of the blank, or both.

An upper forming die 61 is mounted in a die holder 62 upon the upper bolster plate 13. Said upper forming die 61 is provided with a forming recess 63 of such shape as to force the blank against the auxiliary forming member or forming rod 37 to complete the forming operation. One or more inclined surfaces 64 project from the upper forming die 61 and adjoin the forming recess 63. These inclined surfaces 64 present a converging mouth on the forming die and engage the edges of the preformed blank to cam said edges and upper portions of the blank into the forming recess 63. After the edges of the blank 40 have been so cammed into the forming recess of the upper forming die 61, the forming operation is completed in the conventional manner. The conditions just prior to closing of the dies 26 and 62 are depicted in Figs. 5 and 9 while the conditions upon closure of the die are well-known, at which time the blank 21 completely encircles the forming rod 37.

50 A convenient manner of providing said inclined surfaces on forming die 61 is to provide a plurality of vertical ridges 61' along each side thereof. The lower edges of such ridges 61' are beveled to provide the desired camming surfaces while the ridges 61' interengage with the projections 30' and 31' on the auxiliary forming blocks 55 30 and 31 accurately to guide dies 26 and 61 toward each other.

The upper forming die 61 moves upwardly with the upper bolster plate 13 and the forming rod 37, carrying the now tubular blank 21, is moved out of the lower forming die 26 by said kicker pins 58 and 59. The completed tube is removed from the forming rod 37 by an ejector mechanism including a sleeve member 65 slidable upon forming rod 37 and connected by links 66 to the arms of a yoke member 67. Said yoke member 67 is mounted upon a slide movable within a recess of base member 10 and actuated in any desired manner to draw sleeve member 65 along forming rod 37 and to eject the formed tube over the end of rod 37.

70 In the formation of tubes constituting the core of a spool, it is often desirable to form slots in the periphery of such tubes. Accordingly, the forming rod 37 may be provided with a recess 69 and with a pair of slots 70, see Figs. 5, 7 and 75

8. A punch 71 moves through a slot in the lower forming die 26, is actuated by a lever 72 pivoted in a block 73 upon lower bolster plate 11, and held in retracted position by a spring 74 between lever 72 and lower bolster plate 11. An actuator rod 75 is mounted upon the upper bolster plate 13 and is so positioned and arranged as to strike the outer end of lever 72 after the upper forming die 61 is nearly closed, as shown in Fig. 5, and to move punch 71 into the recess 69 of the forming rod 37. The blank 21 is preferably slotted so that the punch 71 merely bends the edges of the blank 21 inwardly. The slots 70 are provided along forming rod 37 to permit movement of the formed tube along the rod 37 by the previously described ejector mechanism.

The perforated blanks 21 are moved from the punch press to the forming press by a transfer mechanism. A slide 76 is slidably mounted within a recess in base member 10 and carries a support 77. A transfer bar 78 is slidably mounted in support 77 and has a jaw 79 for extending through blank guiding channels 18 and through guide channel 53 of guide 38. Said jaw 79 will engage the edge of formed blank 21 in the lower stripper plate 17, see Fig. 1, move said blank 21 through channels 18 and channel 53 onto the upper surfaces of auxiliary forming blocks 30 and 31 of the forming die. At the same time, the upper forming die 61 is moving toward the lower forming die 26 with interengagement of projections 30', 31', and 61' and finally the inclined surfaces 64 upon upper forming die 61 engage the edges of the preformed blank 21 and cam those edges into the forming recess 63 of the upper forming die 61. Closing of dies 26 and 61 completes the forming operation around the rod 37.

Kicker pins 58 and 59 move forming rod 37 out of the lower die 26 upon return of the upper bolster plate to its upper position. Then the ejector mechanism including sleeve member 65 is operated to slide the completed tube over the end of forming rod 37.

45 Since other modifications of the invention may be accomplished without departing from the spirit thereof, the present disclosure is to be construed in an illustrative and not in a limiting sense.

50 Having now particularly described my invention what I desire to secure by Letters Patent of the United States and what I claim is:

1. In a forming press for blanks of sheet stock, the combination with a die provided with a forming recess and a plurality of spaced guide recesses, a second die also provided with a forming recess and having a plurality of inclined projections adjoining and sloping toward said forming recess therein, a pair of supports each carrying one of said dies for movement toward each other, an auxiliary forming member shaped to fit into one of said forming recesses, and an operating means connected to said auxiliary forming mem-

ber and operated in timed relation to the movement of said supports and for moving said auxiliary forming member to force part of said blank into the first die and partially forming said blank prior to the closure of said dies, of a guide member attached to said first die and for engaging the end of said blank continuously to prevent shifting or turning thereof while said auxiliary forming member is partially forming said blank and while the inclined projections of the second die are camming the edges of the blank into the forming recess thereof and are entering said guide recesses.

2. In a forming press for blanks of sheet stock with parallel ends, the combination with a die 15 provided with a forming recess and a plurality of marginal guide recesses, a second die also provided with a forming recess and having a plurality of inclined projections adjoining and sloping toward said forming recess therein, a pair of supports each carrying one of said dies for movement toward each other, an auxiliary forming member shaped to fit into one of said forming recesses, and an operating means connected to said auxiliary forming member and operated 20 in timed relation to the movement of said supports and for moving said auxiliary forming member to force part of said blank into the first die and partially forming said blank prior to the closure of said dies, of a guide member attached 25 to each end of said first die and for abutting the parallel ends of said blank continuously to prevent shifting or turning thereof while said auxiliary forming member is partially forming said blank and while the inclined projections of the second die are camming the edges of the blank into the forming recess thereof and are engaging 30 said guide recesses.

3. In a press for forming a tube from a blank 40 of sheet stock with parallel ends, the combination with a die provided with a semi-cylindrical recess, a second die also provided with a semi-cylindrical recess and having inclined surfaces adjoining and sloping toward each margin of said recess, a pair of supports each carrying one 45 of said dies for movement toward each other, a rod having a diameter equal to the inside diameter of the finished tube, and an operating means connected to said rod and operated in timed relation to the movement of said supports and for moving said rod and part of said blank into the recess of the first die partially to form the blank, of flat guide members at each end of said first die to engage the parallel ends of said blank continuously, each provided with an opening to permit said rod to be moved into forming position, and an interlocking connection comprising at least one guide recess in one die and a corresponding projection on the other die which enters and engages said guide recess as the dies are 50 moved to closed position.

HAYWOOD G. DEWEY.
